Primary Examiner — Austin Murphy(74) *Attorney, Agent, or Firm* — Fox Rothschild LLP(57) **CLAIM**

The ornamental design for a tattoo machine, as shown and described.

DESCRIPTION

FIG. 1 is a perspective view of the tattoo machine of the present invention.

FIG. 2 is a front view of the tattoo machine shown in FIG. 1.

FIG. 3 is a left side view of the tattoo machine shown in FIG. 1.

FIG. 4 is a top view of the tattoo machine shown in FIG. 1.

FIG. 5 is a bottom view of the tattoo machine shown in FIG. 1.

FIG. 6 is a back view of the tattoo machine shown in FIG. 1; and,

FIG. 7 is a perspective view of the tattoo machine shown in FIG. 1.

In the drawings, the broken lines are shown for illustrative purposes only and form no portion of the claimed design.
